CLAIM

The ornamental design for a display screen with transitional graphical user interface as shown and described.

DESCRIPTION

FIG. 1 is a front elevational view of a first image in a sequence according to a first embodiment of a display screen with transitional graphical user interface.

FIG. 2 is a front elevational view of a second image in a sequence according to a first embodiment of a display screen with transitional graphical user interface.

FIG. 3 is a front elevational view of a third image in a sequence according to a first embodiment of a display screen with transitional graphical user interface.

FIG. 4 is a front elevational view of a first image in a sequence according to a second embodiment of a display screen with transitional graphical user interface.

FIG. 5 is a front elevational view of a second image in a sequence according to a second embodiment of a display screen with transitional graphical user interface.

FIG. 6 is a front elevational view of a third image in a sequence according to a second embodiment of a display screen with transitional graphical user interface.

FIG. 7 is a front elevational view of a first image in a sequence according to a third embodiment of a display screen with transitional graphical user interface.

FIG. 8 is a front elevational view of a second image in a sequence according to a third embodiment of a display screen with transitional graphical user interface.

FIG. 9 is a front elevational view of a third image in a sequence according to a third embodiment of a display screen with transitional graphical user interface.

FIG. 10 is a front elevational view of a first image in a sequence according to a fourth embodiment of a display screen with transitional graphical user interface.

FIG. 11 is a front elevational view of a second image in a sequence according to a fourth embodiment of a display screen with transitional graphical user interface.

FIG. 12 is a front elevational view of a third image in a sequence according to a fourth embodiment of a display screen with transitional graphical user interface.

FIG. 13 is a front elevational view of a first image in a sequence according to a fifth embodiment of a display screen with transitional graphical user interface.

FIG. 14 is a front elevational view of a second image in a sequence according to a fifth embodiment of a display screen with transitional graphical user interface.

FIG. 15 is a front elevational view of a third image in a sequence according to a fifth embodiment of a display screen with transitional graphical user interface.

FIG. 16 is a front elevational view of a first image in a sequence according to a sixth embodiment of a display screen with transitional graphical user interface.

FIG. 17 is a front elevational view of a second image in a sequence according to a sixth embodiment of a display screen with transitional graphical user interface.

FIG. 18 is a front elevational view of a third image in a sequence according to a sixth embodiment of a display screen with transitional graphical user interface.

FIG. 19 is a front elevational view of a first image in a sequence according to a seventh embodiment of a display screen with transitional graphical user interface.

FIG. 20 is a front elevational view of a second image in a sequence according to a seventh embodiment of a display screen with transitional graphical user interface; and,

FIG. 21 is a front elevational view of a third image in a sequence according to a seventh embodiment of a display screen with transitional graphical user interface.

The features shown in broken lines do not form part of the claimed design. The subject matter in this patent includes a process or period in which an image changes into another image. This process or period forms no part of the claimed design.
